INVENTOR
Charles H. Plumer,
BY
Frank C. Fischer.
ATTORNEY

UNITED STATES PATENT OFFICE.

CHARLES H. PLUMER, OF NEWARK, NEW JERSEY.

CIGARETTE-HOLDER.

1,389,842.

Specification of Letters Patent. Patented Sept. 6, 1921.

Application filed January 12, 1920. Serial No. 350,877.

To all whom it may concern:

Be it known that I, CHARLES H. PLUMER, a citizen of the United States, residing in the city of Newark, county of Essex, and 5 State of New Jersey, have invented certain new and useful Improvements in Cigarette-Holders, of which the following is a full, clear, and exact description, such as will enable others skilled in the art to which it pertains to make, construct, and use the same, reference being had to the accompanying drawings, and to numerals of reference marked thereon.

15 My invention relates to cigarette-holders characterized by the provision of means for automatically ejecting cigarettes from the holder.

An object of the invention is to provide a simple, inexpensive and attractive cigarette-20 holder.

25 I attain the above and other objects of my invention by the structure conventionally disclosed in the accompanying drawings, wherein similar characters of reference indicate corresponding parts in all the views.

Figure 1 represents, a side elevation of a cigarette-holder, comprising an embodiment of my invention.

30 Fig. 2 represents, a longitudinal section through the cigarette-holder in operative position.

35 Fig. 3 represents, a similar section showing the holder in the normal or inoperative position after a cigar or cigarette butt has been ejected therefrom; and

Figs. 4 and 5 represent, respectively, a side and an end elevation of the ejector.

40 Referring to the drawings, I have shown a cigar or cigarette-holder comprising a cigarette-holding member 1 and a mouth-piece 2 which may be fashioned from wood or any other suitable material. The mouth-piece has a bore 3 therethrough and the cigarette-holding member has a similar bore 4 therethrough, of slightly larger diameter 45 than the bore 3, terminating in a cavity 5 to receive one end of a cigarette.

An annular member or band 6 is secured upon the cigarette-holding member 1, so that 50 the mouth-piece can move freely toward and away from the cigarette-holding member 1.

55 The cigarette butt ejector consists preferably of an aluminum tube 7, one end of which is provided with a circular head 8 which may be formed integral with said

tube or secured thereto in any desired or convenient manner. One end of the tube is secured in the bore 3 of the mouth-piece 2.

A spring 9 is arranged upon the tube 7 and engages the adjacent ends of the cigarette-holding member 1, and the mouth-piece 2, tending to separate them as shown in Fig. 2.

By forcing the mouth-piece inward against the tension of the spring, toward the cigarette-holding member, the flange or head 8 of the tube 7 is moved into the recess or cavity 5 of the cigarette-holding member 1, and then serves to eject therefrom the butt of a cigarette 10 as shown in Fig. 3.

70 It will thus be understood that while the band 6 is shown secured to the cigarette-holding member 1, it can just as well be fastened upon the mouth-piece, and be movable with the respect to the cigarette-holding member, if the parts are not tapered.

I prefer to make the tube and its attached head of aluminum and the mouth-piece and the cigarette-holding member may be fashioned from wood, hard rubber, meerschaum, 80 amber or other suitable material.

Although I have shown all of the parts as of circular cross section, it is to be understood that they may be of oval cross section.

85 The term cigarette-holding member as used in the claims is intended to include any equivalent thereof adapted to hold stogies, cigars or the like.

Experience has demonstrated that the organization above described is a highly efficient one, and while I have shown the preferred embodiment of my present invention, I do not wish to be limited to the exact details of construction shown and described, as obvious modifications thereof, not involving the exercise of invention, may be made by any skilled mechanic, and such departures from what is herein set forth, I consider within the scope and terms of my claim.

100 Having thus described my invention, what I claim as new and desire to secure by Letters Patent is:

105 A device of the class described, comprising a cigarette-holding member provided with a bore therethrough terminating in a cavity located in one end thereof, a mouth-piece provided with a bore therethrough slidably secured to said cigarette-holding member, an aluminum tube one end of which

is secured in said mouth-piece and the other end of which is located in the bore of the cigarette-holding member, a perforated flattened disk secured to the end of the tube located in the bottom of said cavity, adapted to normally close the bore of the cigarette-holding member and to be projected forward in said cavity, and a spring arranged upon the tube and engaging the ends of the

cigarette-holding member and said mouth-piece tending to separate them.

This specification signed and witnessed this 9th day of January, 1920.

CHARLES H. PLUMER.
